Primary Examiner — Robert M Spear*Assistant Examiner* — Kendra L Hamilton(74) *Attorney, Agent, or Firm* — Marshall, Gerstein & Borun LLP(57) **CLAIM**

We claim the ornamental design for a lid for beverage container, as shown and described.

DESCRIPTION

FIG. 1 is a perspective view of a lid for beverage container according to the new design;

FIG. 2 is a left side view of the lid for beverage container shown in FIG. 1;

FIG. 3 is a right side view of the lid for beverage container shown in FIG. 1;

FIG. 4 is a rear view of the lid for beverage container shown in FIG. 1;

FIG. 5 a front view of the lid for beverage container shown in FIG. 1;

FIG. 6 is a top view of the lid for beverage container shown in FIG. 1, and,

FIG. 7 is a bottom view of the lid for beverage container shown in FIG. 1.

Features shown in broken lines in the drawings are not part of the claim.
